C. F. CORGAN.
TELEPHONE RECEIVER HOLDER.
APPLICATION FILED APR. 24, 1918.

1,281,767.

Patented Oct. 15, 1918.

INVENTOR:
Charles F. Corgan,

BY
Joseph Lathem,
ATTORNEY.

UNITED STATES PATENT OFFICE.

CHARLES F. CORGAN, OF PORTLAND, OREGON.

TELEPHONE-RECEIVER HOLDER.

1,281,767.

Specification of Letters Patent. Patented Oct. 15, 1918.

Application filed April 24, 1918. Serial No. 230,568.

To all whom it may concern:

Be it known that I, CHARLES F. CORGAN, a citizen of the United States of America, and a resident of the city of Portland, in the 5 county of Multnomah, in the State of Oregon, have invented certain new and useful Improvements in Telephone-Receiver Holders, of which the following is a specification, reference being had to the accompanying drawing.

My invention relates to devices for supporting a telephone receiver in operative proximity to the transmitter and by means of a supporting member which carries an 15 element adapted to engage and disengage the switch lever of the telephone instrument in such manner as to effect a depression of the lever when the said member is rotated horizontally into position and to release the 20 lever when the element is rotated to another position.

The object of my invention is to provide means for the use of a telephone instrument without the necessity of manipulation, 25 whereby both hands of the operator are left free to be used for writing or otherwise.

What constitutes my invention will be hereinafter specified in detail and succinctly set forth in the appended claims.

In the accompanying drawings, Figure I 30 is a side elevation of a telephone instrument looking toward the switch lever, which is broken away to illustrate the operative relationship of my device thereto, my holder being in the lever-engaging position. Fig. 35 II is a similar view showing my holder rotated out of engagement with the lever, the upward movement of the lever being indicated by dotted lines which show the position it occupies when depressed.

Referring to the numerals on the drawing, 1 indicates a pedestal and 2 its column, surmounted by a mouth piece or transmitter 3, adjustably carried upon a neck 4. 5 indicates the ordinary switch lever and 6 the receiver with its usual wiring, as indicated at 7, through the pedestal. The instrument embracing the elements 1 to 7, inclusive, constitutes a telephone stand of the usual 50 type in familiar use, and is presented only for purposes of explanation. Since it constitutes no part of my invention, it needs no detail description, but only brief identification of its parts.

My invention consists of a holder by which 55 the receiver 6 may be supported upon the

pedestal 1 in operative juxtaposition to the mouth-piece 3, and in such manner that when desired it may be made by a simple movement automatically to actuate the lever 60 5. The shape of the holder and the connection therewith of the receiver 6 are preferably such that when the holder is rotated to release the lever 5 it will necessarily bring the transmitter and the receiver substantially at right angles to each other, in which position the transmitter and receiver are ready for service. When the holder is turned to depress the lever 5, the transmitter and receiver are thereby placed out of position 70 for service and their relative positions will signify the fact as effectually as the hanging of the receiver upon the hook of the lever 5 now indicates it.

For the sake of economy and simplicity I 75 prefer to construct my holder of a single piece of wire shaped to form an intermediate portion or arm 9, having at one end a receiver supporting piece 10 and at the other a neck engaging member. The supporting 80 piece 10 is preferably curved to conform to the shape of the receiver 6 as indicated and is preferably provided with depressions 11 and 12 adapted to receive the hooks 13 and 14 of a loop 15 if said loop is made detachable. The loop may be detachable and 85 united to the member 10, as shown clearly in Fig. I, and is adapted to effectually secure the receiver 6 to the free end of the member 9.

At the end of the arm 9 opposite to that which carries the supporting piece 10, I provide an arm support comprising preferably a collar 17 adapted partially to encircle the neck 4 and affording means for rotatably securing the member 9 thereupon. The arm 9 is also provided adjacent to the collar 17 with a lever-engaging member 18. It may be conveniently made by bending the wire of which the member 9 is composed 100 preferably at a slight inclination but substantially at right angles to the member 9, as clearly shown in Fig. I. The inclination of the member 18 shown affords means for effecting a gradual depression of the lever 5 when it is operated for the purpose. Above the member 18 the collar 17 is formed preferably by bending the wire, and between it and the collar there are formed two sections 19 and 20 that are separated by a space 105 110 sufficient to accommodate between them the vibratory movement of the lever 5. The sec-

tion 20 is preferably prolonged into a terminal ring 21 by which the entire holder may be conveniently rotated by thumb pressure.

The member 9 is rotatably secured to the neck 4 by any suitable means, for example, a clip 22 that partially surrounds the top of the column 2 and terminates in hooks 23 and 24 which, by the resiliency of the clip 22, serve to engage the sections 19 and 20, respectively, and to hold the parts rotatably but firmly in required position. The distance between the collar 17 and the clip 22 affords firmness of support for the arm 9 upon the telephone stand.

The two positions of the member 9, with parts appurtenant thereto, are shown in the two figures of the drawing, respectively. When the telephone instrument is out of service the member 18 is rotated until it engages the lever 5 and depresses it to operate its switch in the ordinary way. At such time the receiver 6 is brought in front of the mouth-piece 3 so as to obstruct the latter and practically cut it out of service. When the receiver is turned sufficiently to uncover the mouthpiece 3, the member 18 automatically by such movement releases the lever 5 and makes circuit for service.

It should be observed that while the member 9 should be of sufficient rigidity to afford a stable support for the receiver 6, it is at the same time desirable to have it so flexible that it may be bent to suit the individual preference of the operator in locating the relative positions of the receiver and mouth-piece when in service, some operators preferring to have the receiver closer to the ear and more sharply at right angles thereto than others.

The form of embodiment of my invention above specified is preferred, because it is readily applicable to a telephone instrument simply by the adjustment of the loop 15 to hold the receiver and the clip 22 operatively

to secure the member 9 in place upon the instrument. With equal facility the parts may be easily and quickly disengaged from the instrument whenever occasion may require.

What I claim is:

1. In a telephone receiver holder, the combination of an arm provided at one end with means of securing to it a receiver and at the other end with an arm support provided with a lever-engaging member disposed upon one side of an opening therein within which the telephone switch-lever may vibrate, and means for rotatably securing said support to a telephone instrument, whereby the switch-lever may be brought opposite said opening or said engaging member at will. 50

2. In a telephone receiver holder, the combination with an arm provided at one end with means for securing to it a receiver, of an arm support at the other end of said arm comprising a collar, a lever-engaging member, intermediate separated sections, and a clip provided with hooks adapted to engage said sections and thereby rotatably and operatively secure said support upon a telephone instrument. 60

3. A telephone receiver holder consisting of a single piece of wire bent to form an intermediate arm, means at one end for securing to it a receiver, and an arm support at the other end thereof, said support comprising a switch-lever engaging member, and adjacent thereto separated sections, between which, in use, said lever may vibrate. 70

In testimony whereof, I have hereunto set my hand in the presence of two subscribing witnesses.

CHARLES F. CORGAN.
